ROBERT B. MADDOX, OF ELK, CALIFORNIA

CARPENTER'S LEVEL

Application filed September 6, 1927. Serial No. 217,698.

The present invention relates to improvements in carpenters' levels and its main object is to simplify the construction of a level of the character described by reducing the 5 number of bulbs usually employed for taking vertical and horizontal readings to a single one.

It is particularly proposed in the present invention to provide in combination with the 10 well-known straight edge of a carpenter's level a circular bulb allowing a reading to be conveniently taken with the straight edge, whether disposed vertically or horizontally.

Further objects and advantages of my invention will appear as the specification proceeds.

The preferred form of my invention is illustrated in the accompanying drawing, in which

20 Figure 1 shows a plan view of a carpenter's level made in accordance with my invention;

Figure 2, a section taken along line 2—2 of Figure 1; and

Figure 3, a view similar to that of Figure 25 1, but showing the level in actual use in connection with a vertical element.

While I have shown only the preferred form of the invention, I wish to have it understood that various changes or modifications 30 may be made within the scope of the claim hereto attached without departing from the spirit of the invention.

In its preferred form my carpenter's level comprises the conventional bar 1 having one 35 or more straight edges 2, and a bulb 3 mounted within the confines of said bar. The bulb is preferably made in the form of a circular ring allowing a liquid contained therein to seek its level on opposite sides no 40 matter what position the level occupies.

The circular bulb may be mounted in the bar 1 in any suitable manner, for instance as illustrated in Figure 2 where the ring-shaped bulb is shown as being inserted 45 through a cylindrical aperture 4 in the center of the bar to come to rest on an internal shoulder 5, and as being held in place by two frusto-conical holding members 6 resting on frusto-conical seats 5' and bearing on opposite faces of the bulb and secured by screws 7.

55 Markings 8 are provided on the bar itself or the frusto-conical elements secured thereto, and not on the bulb as is now the common practice. The markings preferably include two lines on opposite sides of the bulb and running parallel to one of the straight edges, and two other lines arranged at right angles to the former lines.

The bulb is filled with liquid to one-half of its capacity, so that when one of the straight 60 edges 2 is disposed horizontally, the surface of the liquid within the bulb is readable with two of the lines, and when the straight edge is disposed vertically the surface of the liquid is readable with the other two lines.

65 It should be understood that the form of the bulb may be changed to some extent without a departure from the present invention, although I consider the circular ring shown in the drawing as the best embodiment of 70 my idea. Any other form of ring or endless tube, or symmetrical hollow body allowing the liquid level to be readily compared with the markings on the bar, might allow the function to be performed in a similar manner. The advantages of this form of level 75 may be readily understood from the foregoing description. The fact that the markings are provided on the bar instead of on the bulb facilitates the assembly of the device 80 since no attention need be paid to the positioning of the bulb apart from the proper centering of the same. The use of a single bulb for both horizontal and vertical surfaces makes the entire device more simple 85 and less costly, and the provision of a single bulb also facilitates the manipulation of the device.

89 I claim:

In a level of the character described, a straight-edge formed with a transverse perforation defined by a central cylindrical section and an internal annular shoulder and two frusto-conical sections joining the 95 cylindrical section and the shoulder respectively, a liquid carrying annular bulb adapted to be guided through the cylindrical section and to be seated on the shoulder, two frusto-conical elements seated on the frusto-conical 100

sections and bearing on the bulb for holding the same in place and means for securing the latter elements to their seats, the bulb being visible from opposite sides of the straight edge and no part of the holding means projecting beyond the surface thereof.
